UNITED STATES PATENT OFFICE

CHARLES BOOTE, OF JACKSONVILLE, FLORIDA

FILING DEVICE

Application filed September 24, 1928. Serial No. 308,008.

This invention relates to filing devices. It is an object of the invention to provide a device which may readily be attached, for example, to a drawer in a filing cabinet to provide adjustable partitions in the drawer.

A further object is to provide the adjustable partitions in such drawers with locking means for securing them in place.

Further objects and advantages of the invention will become apparent as the description proceeds.

Referring to the accompanying drawings, which are made a part hereof and on which similar reference characters indicate similar parts,

Figure 1 is a perspective view of a filing cabinet showing my device secured upon one of the drawers,

Figure 2, a vertical section through one of drawers showing my invention,

Figure 3, a perspective view of a detail showing the locking device,

Figure 4, a modified form of the device, and

Figure 5, a further modified form.

In the drawings numeral 10 indicates a filing cabinet having a number of drawers 11. These drawers may be of well-known construction which have upstanding bars 12 on the sides of the drawer, or on the inner side of the front end 13. In constructions not provided with such bars I secure bars to the inner sides of the drawer. On the inner sides of the drawer at its rear end I secure other upstanding bars 14. To the upper ends 30 of bars 12 and 14 on each side I secure a rail 15 having spaced notches 16 in its upper side. The bottom of the drawer is provided with spaced notches corresponding to the notches 35 in the rails 15. Cross bars 17 having partition plates 18 secured thereon have their ends adapted to engage the notches 16 in the rails 15 while the lower end of the plates 18 engage the notches in the bottom of the drawer.

The bars 17 have hook-like ends 19 which extend down over the sides of the rails 15. In order to hold the bars 17 against accidental displacement I provide clamps 20 which have ears 21 and 22. When the hook-like end 19 is placed over the rail 15 with the ends of the

bar 17 in the notch 16 the clamps 20 are moved over against the rails 15 so that the ears 21 and 22 extend above and below the rails 15. This prevents the bars 17 from being lifted out of the notches 16. In order to keep clamp 55 in place I may provide a slight indentation 23 in the bar 17 and a corresponding lug or hump 24 on the inner side of the clamp. When the clamp is moved into holding position the hump will slide into the depression 23 and 60 hold the clamp in locked position. Burrs 25 on the ends of the bar 17 prevent the clamps 20 from sliding off the ends of the bar.

In order to provide the bottoms of the drawers with grooves I may use a corrugated 65 sheet-material such as corrugated cardboard or corrugated metal. This provides an inexpensive grooved bottom for drawers and makes them readily convertible into drawers with which my partitions may be used. 70

Instead of the clamps 20 I may make ears integral with the plate 18 as shown in Figure 4. In this form I make the plates 18' in two sections and have these sections 75 slideable on the bar 17. The outer upper edge of each plate is provided with ears 21' and 22' which extend over and under the side rails 15.

Instead of having the clamps on the partition plate I may place them on the side rail 80 as shown in Figure 5. In this form of the invention I provide clamps 20' which slide on side rails 15'. The partition plates 26 may be stamped from a single sheet of material. 85

While I have shown my invention in connection with a filing cabinet, it of course is not limited to that use as it will readily lend itself to any system of boxes or drawers in which it is desired to have adjustable partitions. 90

It will be obvious to those skilled in the art that various changes may be made in my device without departing from the spirit of 95 the invention, and I therefore do not limit myself to what is shown in the drawings and described in the specification, but only as set forth in the appended claims.

Having thus fully described my said inven- 100

tion, what I claim as new and desire to secure by Letters Patent is:

1. In a filing cabinet having drawers therein, means for dividing the drawers into a plurality of compartments comprising a notched rail secured upon each side of the drawer, and a plurality of partition plates having their ends engaging the notches in the said rails and means for locking the plates to the rails, substantially as set forth.
- 10 2. In a filing cabinet having drawers therein, means for dividing the drawers into a plurality of compartments comprising a notched rail secured upon each side of the drawer, a plurality of partition plates having their ends engaging the notches of the said rails, and means for locking the said plates in the said notches, substantially as set forth.
- 15 3. In a filing cabinet having drawers therein, means for dividing the drawers into a plurality of compartments comprising a rail having notches along its upper side secured upon each side of the drawer, a bar having notches at each end adapted to engage in the notches in the said rail, partition plates secured to the said bars, notches in the bottom of the drawer into which said plates may engage and securing clamps slidably mounted on said bars to engage said rails and lock the bars in notches of the same, substantially as set forth.
- 20 4. In a filing cabinet having drawers therein, means for dividing the drawers into a plurality of compartments comprising a rail having notches along its upper side secured upon each side of the drawer, a bar having notches at each end adapted to engage in the notches in the said rails, partition plates secured to the said bars, notches in the bottom of the drawer into which said plates may engage, and means for locking the said bar in the notches on the said rails, substantially as set forth.

In witness whereof, I have hereunto set my hand at Washington, District of Columbia, this 19th day of September, A. D. nineteen hundred and twenty-eight.

CHARLES BOOTE.
